SUNDIAL

Filed Sept. 20, 1930

UNITED STATES PATENT OFFICE

HERMAN NEUWIRTH, OF NEW YORK, N. Y.

SUNDIAL

Application filed September 20, 1930. Serial No. 483,173.

This invention relates to sundials.

Among the objects of the invention is to generally improve the construction of devices of the character described, whereby sundials are provided having parts that are readily adjustable to the requirements for use at any latitude and for compensating for seasonal changes, which shall comprise few and simple parts yet form a neat appearing ornamental structure, which shall be easily and securely set in a desired adjustment, and which shall be cheap to manufacture, and practical and efficient to a high degree in use.

Other objects of this invention will in part be obvious and in part hereinafter pointed out.

The invention accordingly consists in the features of construction, combinations of elements and arrangement of parts which will be exemplified in the constructions hereinafter described and of which the scope of application will be indicated in the following claims.

In the accompanying drawings, in which is shown various possible illustrative embodiments of this invention—

Fig. 1 is a top plan view of the sundial constructed to embody the invention.

Fig. 2 is a fragmentary side elevational view, partly in section, of the improved sundial and mounting therefor showing the construction of the adjustable gnomon, and

Fig. 3 is a fragmentary side elevational view, partly in section, showing a modified form of the improved adjustable gnomon construction.

Referring in detail to the drawings, 10 denotes a sundial constructed to embody the invention. Said dial is seen to comprise a circular face-plate 11, the upper or exposed side 40 of which being engraved, printed or embossed with numerals 12 corresponding to the sun-light hours. Said numerals 12 are preferably of artistic form and are positioned to indicate the spaced radial shadow marker lines 13 which may also be engraved, printed or embossed on the side of the face-plate 11.

On the upper side of the face-plate 11 positioned centrally along a marker line 13a between said shadow marker line 13, an attachment piece 14 is permanently mounted by any

suitable means as for example by spaced countersunk-head screw 15 inserted up through the back side of the face-plate 11 as shown in Fig. 2. The inner end 14a of said piece adjacent the center of the face-plate 11 terminates in a hinge 16 for supporting a gnomon 17 for swinging movement.

The gnomon 17 which is triangular shaped and has an upper straight edge 17a adapted to cast a shadow upon the face-plate 11 for co-operating with the marker line 13 and numerals 12 for indicating the time during sun-light hours in the well understood manner.

The end 17b of the lower side 17c of the gnomon 17 carries an adjusting screw 18 which extends towards the attachment piece 14. A nut 19 preferably formed with a knurled edge is threaded on said screw 18. The attachment piece 14 is provided with an opening 14a in register with the leading end of the screw 18, said opening being adapted to receive the screw and permit the free movement of the screw in and out thereof. A portion 14b of the opening 14 is enlarged and has the nut 19 snugly fitted therein. The nut 19 is thus retained in position by the attachment piece structure but is permitted rotary movement for angularly adjusting the gnomon 17 with respect to said attachment piece 14.

In order that the opening 14a neatly fits about the screw 18, the inner end of said screw is pivoted to the gnomon 17 as at 20 to permit the screw 18 to move linearly while the gnomon 17 swings arcuately.

The practical utility of the sundial 10 will now be apparent. The sundial 10 may be mounted upon a suitable pedestal or base B with the gnomon 17 in the plane of the earth's meridian and at right angles to the normal horizontal place so that the edge 17a of the gnomon 17 casts a shadow on the face-plate during sun-light hours. The face-plate 11 is permanently set either in a normal horizontal plane or in a plane at slight angle to the horizontal plane. The gnomon 17 can then be adjusted for use at the latitude of installation and may be made to compensate for seasonal changes. To this end the nut 19 is simply turned to vary the inclination

of the gnomon edge 17a with respect to the face-plate 11, as indicated by the dotted lines in Fig. 2.

In Fig. 3 a modified form of the invention is shown in which the screw 18 is fixedly mounted in position to project from the end 17b of the gnomon 17 instead of being pivoted thereto as is shown in Fig. 2. This latter construction has the opening 114a into which the screw 18 extends made larger than in the form of the invention described above and shown in Fig. 2 to provide for clearance during the swinging adjustment of the gnomon 17. The enlarged portion 114b of the opening 114 in which the nut 19 is fitted must also be made larger for the same reason. The gnomon 17 shown in Fig. 3, is also adjusted and set by simply turning the nut 19 in the same manner as described above for the sundial 10.

It will thus be seen that there is provided sundials whereby the several objects of this invention are achieved and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. In a sundial construction, an attachment piece adapted to be secured to the face-plate of the sundial, a gnomon movably attached to one end of said piece, a screw projecting from said gnomon spaced from said end, and a nut threaded on said screw, said piece having a portion spaced from said end formed to engage said nut for permitting angular adjustment of the gnomon with respect to said piece.
2. In a sundial construction, an attachment piece adapted to be secured to the face-plate of the sundial, a gnomon, a hinge for fastening the gnomon to said piece, a screw pivoted at one end to project from said gnomon at a spaced distance from said hinge, and a nut threaded on said screw, said piece having an opening in register with the free end of the screw, said opening being enlarged for receiving and retaining the nut to permit the angular adjustment of the gnomon with respect to said piece.

In testimony whereof I affix my signature.

HERMAN NEUWIRTH.
